ROCK WOOL BLOW CHAMBER

Arthur F. Miller, Jackson, Mich., assignor to
Marquette Cement Manufacturing Company, a
corporation of Illinois

Application January 25, 1937, Serial No. 122,326

6 Claims. (Cl. 154—27)

This invention relates to rock wool manufacture and more particularly to a blow chamber into which the mass of wool material and shot is blown.

5 In making rock wool from fused rock wool material, a thin stream of the fused rock is violently disintegrated by a blast of steam or air forming fibers of rock wool and larger so-called "shot" particles. The shot particles, being larger 10 and heavier, tend to settle out more rapidly, and the present chamber is designed to remove as large a proportion of these as practicable, and at the same time to produce continuously a uniform mass or mat of fibrous material.

15 The invention is illustrated in the drawing, in which—

Fig. 1 represents a sectional elevation of the blow chamber; Fig. 2, a sectional plan view taken along the line 2—2 in Fig. 1; and Fig. 3, a cross section taken at the point 3 in Fig. 1.

20 In producing rock wool, rock wool material is melted as desired, for example in the cupola (not shown) and a thin stream of the molten material from the cupola is blasted by a jet of steam or air 25 forming fibers and shot which enter the chamber at the entrance 10, as shown in Fig. 1. An endless belt 11 carried by the driven wheels 12 and 13, is positioned below the entrance and is of such length as to catch a large portion of the shot 30 material and any heavy unblown slag. The wheels 12 and 13 are so driven as to rotate the belt in the direction shown by the arrow, carrying the heavier material out of the chamber and into the cinder pit 14. A flexible guard 15 is positioned above the belt to restrict the amount of 35 gas which may leave the chamber around the belt. A similar guard may be provided below the belt, if desired.

The belt 11 is upwardly inclined to provide a 40 baffle and may extend into the chamber a considerable distance, for example, as much as ten or twelve feet from the mouth.

Beneath the mouth 10 is a plate 16, downwardly 45 inclined, which extends out over the lower portion of the belt 11 and is provided with a downward extension 17 upon which the flap 15 is carried. The roof 18 of the chamber is built in several sections to provide a stream-line effect and to avoid, so far as possible, the setting up of 50 undesirable eddies or currents within the chamber. The first section 19 of the roof extends from the entrance 10 to a point 20 roughly above the end of the belt 11, the angle of the section 19 being substantially that of the belt. The deviation of 55 the plate 16 and of the roof section 19 from the

horizontal are approximately equal, although in opposite directions.

The center section 21 of the roof is approximately horizontal and covers approximately three-sevenths of the conveyor belt 30, which will 5 be hereinafter described. The third section 22 of the roof is downwardly inclined at an angle slightly less than that of section 19, and covers about half of the remainder of the belt, while section 23 continues downward at a greater angle 10 covering the remaining portion of the belt 30.

It will be noticed that this configuration of the roof directs the incoming gases downwardly toward the belt 30 without the provision of any dead air spaces within which eddies can be set 15 up. With light material, such as rock wool, any substantial eddy will cause material to be held in the air until it has reached considerable weight after which it will fall regardless of the eddy. Such falls, however, will produce irregularities in 20 the mat upon the belt.

The belt 30, which is to receive the wool fibers, is preferably of a foraminous texture and is mounted upon the rollers 31, 32, 33, 34 and 35, which are driven to rotate the belt in the direction of the arrow and carry the wool fibers out of the chamber at the opposite end from the entrance 10. Beneath the belt are mounted a plurality of suction chambers 36, each of which is provided with an exhaust 37. The exhaust may 30 feed into a manifold or may be individually controlled. In the latter case, it is possible to obtain greater uniformity in the ribbon of rock wool produced, by progressively increasing the vacuum in the direction of movement of the wool material. 35

The belt 30 is preferably below the baffle belt 11.

The area controlled by each chamber is preferably small, for example not substantially more than four or five feet.

At the exit side of the blow chamber, means are 40 provided for compressing the mineral wool deposited on the belt 30. This means preferably comprises a belt 40 on rollers 41, 42 and 43, the roller 42 having its axis below a line connecting the axes of rollers 41 and 43 to provide an outwardly curved portion on the lower side of the belt, or, if desirable, a fourth roller may be inserted for this purpose.

Inasmuch as the thickness of material on the belt increases toward the exit side of the chamber, it is preferable to progressively increase the vacuum on the suction chambers in the same direction, in order to utilize the depositing surface of the belt to the maximum extent.

Likewise, the shape of the chamber already de-

scribed is such as to tend to equalize the velocity at the front and rear of the belt 30, thereby delivering substantially uniform amounts of material to the various portions of the belt, and increasing the effectiveness of the depositing area.

In blow chambers now in general use, escape vents are provided for steam and air entering the chamber at the low point. The escaping air or steam carries with it light and fine parts of rock wool fibers in amounts sufficient to cause considerable loss over a long period, and at the same time the subsequent settling of the material outside constitutes a nuisance. In the present design this problem is completely solved because the ribbon of material acts as a filter body for such fine material through which all of the outgoing gas must pass.

The side walls 18 of the blow chamber are preferably substantially vertical or converge slightly toward the belt, thereby insuring proper settling conditions.

The foregoing detailed description has been given for clearness of understanding only and no unnecessary limitations should be understood therefrom, but the appended claims should be construed as broadly as permissible in view of the prior art.

I claim:

1. In a rock wool blow chamber; the combination of means for blowing molten wool rock into a chamber, a foraminous conveyor within the chamber, and a plurality of suction means arranged progressively along the conveyor and operating therethrough, the suction means being adapted to produce a progressively higher vacuum in the direction of movement of the conveyor.

2. In a rock wool blow chamber; the combination of means for blowing molten wool rock into the chamber, a foraminous conveyor within the chamber, and means for subjecting the conveyor to progressively higher vacuum in the direction of its movement.

3. The method of blowing rock wool, which comprises melting wool rock material, disintegrating a stream of the molten material to produce rock wool fibers, directing the formed fibers into a settling chamber wherein they are permitted to settle upon a conveyor, and subjecting

the conveyor to a progressively increasing vacuum in the direction of its movement.

4. In combination with means for producing and blowing molten rock wool material, a chamber having an opening at one end associated with the means for blowing the rock wool material, said chamber having substantially vertical side walls, a foraminous conveyor substantially of the same width as the chamber longitudinally arranged therein, means for exhausting gas through the conveyor, said chamber having a roof, the conveyor and the roof of the chamber being positioned to approach each other in the direction of movement of the conveyor, said conveyor being adapted to move in a direction away from the introduced rock wool material.

5. In combination with means for producing and blowing molten wool rock material to produce rock wool fibres and shot; a blow chamber having an entrance and exit, an upwardly inclined conveyor near the entrance of the chamber adapted to receive shot and move it downwardly from the chamber, a second conveyor nearer the exit of the chamber than the first and positioned below the upper end of the first conveyor, said chamber having substantially vertical side walls, said second conveyor having substantially the width of the chamber, and the roof of the conveyor being substantially parallel to the first conveyor throughout its length and approaching the second conveyor substantially throughout its length, and means beneath said second conveyor for removing gases from the chamber, said chamber being sealed to prevent escape of gases except through said second conveyor.

6. In combination with means for producing and blowing molten rock wool material, a chamber having an opening at one end associated with the means for blowing the rock wool material, a conveyor longitudinally arranged within the chamber, means for exhausting gas through the conveyor, said exhausting means being substantially the only escape for gases from the chamber, and the chamber have substantially vertical walls and a roof gradually approaching the conveyor in the direction of its movement, and said conveyor being adapted to move in a direction away from the introduced rock material.

ARTHUR F. MILLER.
